FIREPLACE IRON

Donald E. Hodge, 7010 Pacific Ave.,
Olympia, Wash. 98501

Filed Mar. 31, 1966, Ser. No. 1,711

Term of patent 14 years

(Cl. D81—6)

Fig. 1.

Fig. 2.

Fig. 3.

Fig. 4.

Fig. 5.

FIGURE 1 is a front perspective view of a fireplace iron showing my new design;

FIGURE 2 is a side elevational view thereof, both sides being alike;

FIGURE 3 is a top view thereof;

FIGURE 4 is a front view thereof; and

FIGURE 5 is a rear view thereof.

I claim:

The ornamental design for a fireplace iron, as shown and described.
